FLANGE

Harold M. Sheridan, New Boston, Ohio

Application December 30, 1940, Serial No. 372,379

1 Claim. (Cl. 285—49)

This invention relates to improvements in flanges or spouts, more particularly adapted for use with barrels, drums and the like.

One object of the invention is to provide a flange which may be quickly pressed into place on a metal tank or drum in such a manner that it will be leak-proof, non-displaceable, and will have high resistance against torsional strain.

Another object of the invention is to provide a flange which is characterized by the utmost 10 simplicity in construction and durability in use.

A further object of the invention is to provide a flange which, in one embodiment, has an externally threaded portion for use with certain types of containers and, in another embodiment has an internally threaded portion for use with the conventional type steel drum.

A still further object of the invention is to provide a flange which, in a still further embodiment, is entirely unthreaded so that it will lend itself readily for use in conjunction with the metal type beer barrel.

And still another object of the invention is to provide a flange which, in still another embodiment, may be readily used in conjunction with containers for wine and milk.

Other objects of the invention, not particularly mentioned hereinbefore, will become apparent during the course of the following description.

In the drawings forming a part of my application:

Figure 1 is a transverse vertical sectional view showing my improved flange,

Figure 2 is a vertical transverse sectional view showing a modified embodiment of my flange,

Figure 3 is a vertical transverse sectional view showing a still further embodiment,

Figure 4 is a vertical transverse sectional view showing still another modified form of my flange,

Figure 5 is a detail vertical transverse sectional view showing another modification, and

Figure 6 is a detail transverse sectional view showing still another modification.

Reference is now had more particularly to the accompanying drawings and, specifically, to Figure 1 thereof. The numeral 1 indicates a portion of a steel tank or drum of the type commonly employed for transporting chemicals and the like. It should be understood, in this connection, that the embodiment of my invention as shown in Figure 1 may be employed in conjunction with heavy boilers, tanks and drums wherein practice up to the present time has been to weld the flanges in place. A portion of the drum is apertured at 2 and the margins defining the aper-

ture are pressed upwardly to define a straight portion 3 and laterally to define an overhanging lip or flange 4. A locking recess 5 is formed in the upper surface of the flange or lip 4. The purpose of the locking recess will be set forth in more detail hereinafter.

Associated with the straight portion 3 and the lip or flange 4 is a retaining ring 6, said retaining ring having an annular laterally and inwardly turned portion 7 which is engaged tightly between the lip 4 and the upper surface of the portion of the barrel or drum directly beneath said lip. The retaining ring is provided, at its upper end, with an inwardly displaceable portion 8. This inwardly displaceable portion extends upwardly prior to the assembly of the flange and has a tapered upper edge 8a.

Mounted upon the upper surface of the lip 4 and within the confines of the retaining ring 6 is a body ring 9, said body ring having a smooth outer surface 10 and a threaded portion 11. The body ring is held in association with the retaining ring and the flange 4 by means of the displaceable portion 8. That is to say, after the body ring 9 has been placed in position within the retaining ring, the displaceable portion 8 is pressed inwardly and laterally into overhanging relation with respect to said body ring for clamping the body ring tightly into engagement with the flange 4 and said retaining ring. In order to insure that the body ring will be limited against rotative movement, said body ring is provided with a locking tongue 12 which is engageable within the locking recess 5. It will now be understood that the body ring and retaining ring will be effectively mounted in surrounding relation with respect to the opening 2 and will be held against rotative movement about said opening.

A closure plug 13 is employed for closing the opening 2, said closure plug having a bottom wall 14, an annular externally threaded portion 15 and a laterally directed flange 16. When the closure plug is in position, as shown in Figure 1, the threaded portion 15 will be in engagement with the threaded portion 11 of the body ring 9. The closure plug may be screwed tightly in place for insuring that there will be no leakage from the container or drum past said plug. A gasket 17 is normally employed in conjunction with the plug to provide maximum insurance against leakage.

Reference is now had to Figure 2 of the drawings wherein, as will be seen, a modified embodiment is illustrated. In Figure 2, the numeral 18 indicates a portion of a drum or container, par-

ticularly that type of drum which is used for transporting beer. The drum 18 is provided with an opening 19, similar to the opening 2 in the embodiment shown in Figure 1. The margins of the opening 19 are pressed to define an annular straight portion 20 and an annular lip 21. A retaining ring 22, similar to the ring 6, has an annular inwardly directed portion 23 at its lower end, said portion 23 being clamped between the lip 21 and that portion of the upper surface of the container 18 which is disposed directly beneath said lip. The ring 22 is provided with a displaceable portion 24 which, during assembly of the device, projects upwardly.

Associated with the lip 21 and the retaining ring 22 is a body ring 25, said body ring being held tightly in place in connection with the retaining ring 22 and the upper surface of the lip 21 by displacing the portion 24 laterally inwardly in overlying relation with the upper surface of said body ring 25. The body ring 25 is held against rotative movement by means of a tongue 26 which is engageable in a locking recess 27, the body ring having tapered inner surface 28 which is particularly well adapted for receiving a tapered or frusto-conical surface of a bung.

In the embodiment shown in Figure 3 of the drawings, I have shown a flange which is particularly adapted for use in conjunction with milk or wine drums. In this embodiment, a portion of the drum is shown at 29, said drum having an opening 30 surrounded by a pouring neck 31, said pouring neck having, at its outer end, an annular outwardly directed lip 32. Connected with the pouring neck 31 is a body ring 33, said body ring having a threaded portion 34 and a displaceable portion 35, said displaceable portion having an inclined surface 36. The body ring is formed with a shoulder 37 which is disposed at the junction of the displaceable portion 35 with the body ring member. Locking recesses 38 are formed in the under surface of the body ring and normally receive upwardly pressed studs 39 on the portion 29 of the drum for retaining the body ring against rotative movement on the pouring neck.

In assembling the flange according to this embodiment, the ring is placed about the pouring neck before the lip 32 is turned to the position shown. After the ring is in place, the lip 32 is pressed laterally into engagement with the shoulder 37. This action will, of course, retain the ring in tight engagement about the neck 31. The displaceable portion 35 is pressed into tight engagement against the upper surface of the lip 32 for providing insurance against displacement. The projections 39 are upset into the recesses, by pressing, for preventing rotation of the body ring about the pouring neck 31.

A cap 40 is screwed on the threaded portion 34 of the body ring 33 for effectively sealing the pouring neck 31. The cap 40 is of conventional construction and includes an annular internally threaded flange 41 and a top wall 42.

The embodiment shown in Figure 4 of the drawing is quite similar to that shown in Figure 3. However, the embodiment shown in Figure 4 is particularly well adapted for use with drums used for the shipping of milk and milk products and other products wherein an opening is needed that is free of cracks or crevices, which cracks or crevices might collect bacteria. In Figure 4, the numeral 43 indicates a portion of a milk drum, said portion having a pouring neck 44, which pouring neck is provided with a nor-

mally laterally extending lip 45, said lip, however, extending upwardly prior to installation of the body ring employed. The body ring is indicated at 46 and includes a threaded portion 47 and an inner portion 48 defining a shoulder 49. A displaceable portion 50 is formed on the threaded portion 47, and the threaded portion 46 is separated from the portion 48 by means of an annular groove or stop 51. Locking recesses 52 are formed in the under surface of the ring 46 and said locking recesses are adapted to receive studs 53 which are upset from the surface of the portion 43 when the ring is assembled, in a manner now to be described.

15. When the flange, according to the embodiment of Figure 4, is assembled, the ring 46 is first placed about the neck 44. The lip 45 is pressed into overlying engagement with the shoulder 49 and the displaceable portion 50 is pressed in overlying engagement with the lip 45. At the same time, the locking studs 53 are pressed upwardly into engagement with the locking recesses 52 for preventing rotative movement of the ring about the pouring neck.

25. A cap 54, similar to the cap 40, is screwed on the threaded portion 47 of the body portion 46 for sealing the opening.

In Figures 5 and 6, I have shown two further embodiments of the flange shown in Figure 1. 30. These embodiments are to be used in drums of lighter gage metal or smaller size cans and containers.

In the embodiment shown in Figure 5, 55 indicates a portion of a light weight drum or container and said portion is formed with an opening 56, which opening is defined by upwardly pressed portions 57. A body ring 58 is fitted about the portion 57 and is provided with a flange 59. The ring 58 is held in place by pressing outwardly the upper margin of the portion 57 to define a retaining lip 60. The ring 58 is internally threaded at 61 to receive a closure plug of conventional design. The ring 60 may be held against rotation with respect to the drum by means of a mating locking tongue and recess of construction similar to that shown at 5 and 12 in Figure 1.

In Figure 6 of the drawings, a portion of a light weight container is shown at 62 and said portion is pressed upwardly to define an opening 63 and an upwardly projecting portion 64. A body ring 65 is placed about the portion 64 and is provided with an inwardly directed flange or lip 66. The ring is held in place by pressing the upper margin of the portion 64 laterally to define a retaining lip 67. The ring 65 is externally threaded, as shown at 68, to receive a cap similar to the cap 40.

60. Attention is directed to the fact that, by the use of any type of flange shown in the drawings, it will be possible to drain the entire contents from the drum or container due to the fact that the tank metal is turned back for securing the flanges in place and thus a smooth surface is defined. Free flow of the contents will thus be assured.

In view of the locking means employed, it is obvious that flanges formed according to the various embodiments of my invention cannot be knocked or twisted out of their proper locations. Moreover, it is particularly desired to point out that the flange shown in Figure 2 will have great resistance against the force used to drive the bungs into engagement with the body rings 25.

75. It is obvious that suitable gaskets may be em-

ployed in connection with the flanges of each and all of the embodiments shown if, when and where necessary. Also, the flanges of my invention can be equipped with means for permitting cap sealing, or wire sealing and tag holders.

The flanges and plugs may be readily manufactured from pressed steel or forgings if desired, if being well known that pressed steel parts are the most economical to produce. The various parts of the flange are capable of being pressed into place with the utmost facility. As heretofore described, it is only necessary to form the opening in the tank, turn up the margins defining the opening, fit the retainer rings in place, turn the margin defining the opening laterally to lock the retaining ring in place, place the body ring within the retainer ring, and, finally, press the displaceable portion of the retainer ring into engagement with the body ring. The entire flange is held in place by pressing action and the parts are effectively retained against relative shifting movement. In the embodiments shown in Figures 3 and 4, the added step of forcing the studs upwardly into the locking recesses will be effected. This is done, of course, by the same pressing action.

It is well understood that there are flanges or sputts now in use that are threaded externally but all of them require welding or soldering, which operation requires a lot of time and results in a less efficient flange. The use of my flange, in its several embodiments, obviates the need of welding or soldering.

It should be understood that, in the embodiments shown in Figures 1 and 2 of the drawings, the body rings 9 and 25 may be made

of suitable plastic material without departing from the scope of the invention. The advantage for this feature is that plastic material, which will not react with certain chemicals, may be used for the protection of both the chemicals and the flange of the container. Any type of suitable plastic may be employed, such as, for example, Bakelite, laminated cellulose acetate, Polystrene, and the different types of cast resins. In short, any type of plastic material which can be worked into a ring and threaded can be used.

As best seen in Figures 3 and 4 of the drawings, I provide wrench lugs 70 and 71, respectively. These wrench lugs are engageable by a wrench and permit ready removal of the caps 40 and 54, respectively.

It is thought that the construction and use of my improved flange, in the several embodiments described, will now be fully understood.

Having thus described the invention, what is claimed as new is:

In a flange, in combination with a container having an outwardly turned portion defining an opening, a retainer ring surrounding the outwardly turned portion and opening, said outwardly turned portion having a recess and also having a lip engaging the retainer ring for preventing displacement thereof, a body ring above the lip carried within the retainer ring and about the opening, a tongue carried by the body ring for preventing rotative displacement of said body ring, and means carried by the retainer ring and displaceable to overlie the body ring for preventing outward displacement thereof with respect to the retainer ring.

HAROLD M. SHERIDAN.
